**LAMP BASE AND BULB ASSEMBLY
 APPARATUS**

Clarence S. Terez, Maple Heights, Ohio, assignor to General Electric Company, a corporation of New York
 Filed Mar. 7, 1955, Ser. No. 492,558
 6 Claims. (Cl. 29—25.19)

My invention relates generally to apparatus for automatically assembling the base and bulb of an electric lamp or similar device.

More particularly, my invention relates to base threading mechanism of a type wherein a hollow threading needle is inserted through a base and then lowered therewith to bring the end of a lead wire of the lamp into the hollow needle, after which the base is threaded along the needle and the lead wire onto the lamp bulb.

An object of my invention is to provide a device of the character referred to above and of improved construction whereby it is caused to operate with a substantially higher degree of success. In accordance with one aspect of this object, it is a feature of my invention that the base is caused to be, in effect, floated pneumatically to provide freedom for the base to adjust for alignment during insertion of the threading needle therethrough. Another object is the provision of a structure which will assure positive placement of the base on the lamp bulb.

Further features and advantages of my invention will appear from the following description of species thereof and from the drawings wherein:

FIG. 1 is a side elevation of a threading device comprising my invention and shown in operative relation with a support or holding means for a lamp which is to be supplied with a base;

FIG. 2 is a front elevation of the threading device;

FIG. 3 is a plan view of the threader;

FIG. 4 is a side elevation of the threading device showing the relationship of its operating elements during a stage of the threading operation;

FIG. 5 is a front elevation showing the relationship of the operating elements at a succeeding stage in the operation of the device;

FIG. 6 is a fragmentary front elevation showing the operating elements at the moment of completion of the assembly operation; and

FIG. 7 is a fragmentary elevation, in section, of a modified means for providing pneumatic floating of the base.

Referring to FIG. 1, the lamp bulb 1 is brought into operative relation to the threading mechanism by a holder indicated generally at 2 and forming part of a conveyor which carries the lamps from an exhaust machine to a base machine, neither of which have been illustrated. The holder 2 supports the lamp bulb 1 in a vertical position with its top lead 3 extending vertically upward in axial alignment with the lamp.

The base 4 herein illustrated is of a conventional type comprising a screw-threaded shell 5 (FIG. 4) having an insulating web 6 of glass at one end in which is embedded a metal eyelet 7.

The base 4 is inserted, preferably by automatic mechanism not shown, into a base receiver chamber member 8 which is shaped to define a downwardly opening cavity 9 including a roof portion 8' and sides proportioned to receive the base 4 rather snugly and including a shoulder 10 in the roof portion and engageable with the shoulder 11 at the top of the base shell 5. The cavity 9 is in this case also open at one side to receive the base 4. The base receiver 8 is mounted fixedly on a main slide 12 which is mounted for vertical reciprocation on a post 13 extending downwardly from a stationary support arm 14 which may be mounted on the frame of the conveyor 2. Movements

2

of the slide 12 are controlled through a link 15 and arm 16 from an operating rod 17 which is actuated by a cam mounted on the main cam shaft drive of the associated basing machine. The arm 16 is pivoted at one end 17' to the link 15 and at its other end (not shown) on a pin carried by the stationary arm 14.

The bottom of the cavity 9 in the base receiver 8 is closed by a pair of jaws 20 with upper surfaces 20' defining a floor for the cavity and having their meeting faces shaped to define a conical lead wire receiving aperture 18. The jaws 20 include vertically extending arm portions 21 which are pivotally mounted at their upper ends on pins 22 carried by the main slide 12.

A hollow threading needle 23 is arranged vertically above the base receiver 8 with its lower end in an aperture 24 in said receiver and in alignment with the threading aperture 18 in jaws 20. The said needle 23 is carried by a rod 25 which is slidably mounted in a bracket 26 mounted on a sub-slide 27 which is slidably mounted in ways 28 in the main slide 12. The needle 23 and its rod 25 are normally held in their uppermost position by engagement of the shoulder or hook portion 30 of a latch 31 with a finger 32 extending laterally from a collar 33 attached to the upper end of the rod 25. The latch 31 is pivotally mounted at 34 on a pin in a bracket 35 mounted on the main slide 12. The latch 31 is normally urged in a clockwise direction to a vertical position by a spring 36 carried by a screw 37 extending through the latch and secured to the main slide 12.

The needle 23 and rod 25 are urged downward in the bracket 26 by a spring 40 connected between posts on the collar 33 and the bracket 26. The rod 25 is prevented from rotating by engagement of a notched portion of collar 33 with a post 41 (FIG. 3) extending upwardly from the bracket 26.

The slide 12 is prevented from rotating about the post 13 by engagement of a slotted bracket 42 on slide 12 with a post 43 extending downwardly from the arm.

In operation, a base 4 is loaded into the cavity or pocket 9 in the base receiver member 8 and onto the floor defined by the upper surfaces 20' of the closed jaws 20. A suction is applied to the upper end of the chamber 9 through passages 45 (FIG. 2) and flexible conduits 46 to thereby lift the base 4 and bring its shoulder 11 into engagement with the shoulder 10, the eyelet 7 being thus retained a short distance away from the upper wall or roof 8' of the cavity.

The slide 12 is then moved downward through operation of the operating rod 17 to carry downward the base receiver 8 and jaws 20. The needle 23 also moves downward with receiver 8 and jaws 20 by virtue of a frictional connection between the sub-slide 27 and the main slide 12 provided by a friction pad 47 (FIG. 3) carried by sub-slide 27 and urged against slide 12 by a spring 48 which is retained in place by screw 49.

Shortly after the downward movement has started, the needle 23 is released by the latch 31 due to counterclockwise pivoting of said latch 31 by engagement of a cam surface 50 thereon with a dog member 51. The dog 51 is pivotally mounted at 52 on an arm 53 secured to the post 43, and is normally retained in the position shown in FIG. 1 by a spring 54 which is connected between a finger 55 mounted on support arm 14 and a pin 56 mounted on the dog 51 and held by said spring 54 in engagement with the underside of the arm 53.

Upon release of the needle 23 and rod 25, they are pulled downward by the spring 40 to carry the needle 23 through the base eyelet 7 to bring the lower end of the needle 23 into engagement with a locating pocket 57 formed in the jaws 20 at the upper end of the threading aperture 18.

The base receiver 8 and jaws 20, together with needle

23, continue downward to bring the upper end of the lead-in wire 3 into the aperture 18 and into the lower end of the needle 23, as illustrated in FIG. 4. At this time, downward movement of the slide 27 is arrested by engagement of stop nut 58 with a lug 59 on arm 14, the nut 58 being mounted on a screw 60 attached to the upper end of sub-slide 27.

Upon continued movement of the slide 12, the base receiver 8 continues downward to carry the base 4 along the needle 23, and the jaws 20 begin to move apart as illustrated in FIG. 5. The opening movement of the jaws 20 is effected by links 61 each of which is pivotally connected between a pin 62 on the respective arm 21 of jaw 20 and a common pin 63 carried by the lower end of the sub-slide 27. The said links 61 are caused to pivot by virtue of the fact that movement of the sub-slide 27 has been terminated while the jaws 20 continue to move downward. In the closed position of the jaws 20 a tight closure thereof is assured by a spring 64 extending between posts on the jaw arms 21, there being sufficient play in the connection of the links 61 to the respective pins to permit such action of the spring 64.

Continued downward movement of the slide 12 causes the base receiver 8 to carry the base downward beyond the end of the needle 23 and along the wire 3 and to deposit the base 4 onto the end of the bulb 1 as illustrated in FIG. 6. At this time, or just prior to the arrival of the slide 12 at its lowermost position, the vacuum connection through conduits 46 to the cavity 9 is interrupted, and the base 4 is pressed firmly onto the bulb 1 in proper alignment therewith.

During downward movement of the slide 12, after movement of sub-slide 27 has been arrested, the latch 31 is carried therewith to bring its shoulder 30 downward a short distance beyond the arm 32.

The threading mechanism is returned to its original position by upward movement of the slide 12. The sub-slide 27 moves along with the slide 12, carrying needle 23 therewith, until a stop nut 68 on the screw 60 engages the underside of the lug 59. Thereafter, the shoulder 30 of latch 31 is brought into engagement with the underside of finger 32 to carry the needle 23 farther upward. During the short travel of the latch 31 before engaging the finger 32, the base receiver 8 moves upward relative to the needle 23 to bring the end of the needle into the aperture 24 in the top of the base receiver 8. The latching position of the latch 31 is unaffected by the dog 51 which is pivoted counterclockwise about pin 52 by the upper end of the latch 31.

The weight of the slide 12, and the elements mounted thereon, is preferably partially counterbalanced by a spring 69 which is attached to posts on said slide 12 and on the arm 14.

I have illustrated in FIG. 7 a modified means of floating the base 4 within the pocket 9 of the base receiver 8. In this case it is accomplished by air jets through passages 70 within each of the jaws 20', the passages being supplied with air pressure through flexible conduits 71 to direct jets of air into the interior of the base 4. Compressed air is supplied through the conduits 71 when the base 4 is fed to the receiver 8, and the supply of air may be terminated just prior to the terminus of downward movement of the base receiver 8.

What I claim as new and desire to secure by Letters Patent of the United States is:

1. In combination, a holder for supporting a lamp bulb with a lead-in wire extending upwardly therefrom, and a base-threading mechanism comprising a base-receiving chamber member open at its bottom and including a roof having a needle-receiving aperture therein and sides adapted to enclose a base at least partially around its periphery and at a position above and in alignment with the lamp bulb in said holder, a pair of jaws mounted adjacent said chamber member to cover the bottom thereof and define a floor therefor, when closed, and having their meeting faces shaped to define a funnel-shaped wire-

threading aperture aligned with said needle-receiving aperture, a hollow threading needle mounted above said chamber in alignment with the needle-receiving aperture therein and with the wire-threading aperture in said jaws, means for applying a differential air pressure within the interior of said chamber in a direction and amount to supply a flow of air to a base in said chamber sufficient to lift and float the base pneumatically at the top of said chamber and off the floor defined by said jaws, means for lowering the needle through the said needle-receiving aperture and through the base in said chamber into registry with said wire-threading aperture during the application of the differential air pressure whereby the base is free to adjust slightly within the chamber to ensure entry of the needle therethrough, means for then lowering the chamber member, jaws and needle in unison to cause the lead-in wire to enter said needle by way of the said wire-receiving aperture, means for then causing the said jaws to open and uncover the bottom of said chamber member during continued movement of said chamber member to carry the base therein along the needle and the lead-in wire and onto the bulb in said holder, and means for terminating the differential air pressure when said chamber member has approached its lowered position.

2. In combination, a holder for supporting a lamp bulb with a lead-in wire extending upwardly therefrom, and a base threading mechanism comprising a base-receiving chamber member open at its bottom and including a roof having a needle-receiving aperture therein and sides adapted to enclose a base at least partially around its periphery and at a position above and in alignment with the lamp bulb in said holder, a pair of jaws mounted adjacent said chamber member to cover the bottom thereof and define a floor therefor, when closed, and having their meeting faces shaped to define a funnel-shaped wire-threading aperture aligned with said needle-receiving aperture, a hollow threading needle mounted above said chamber member in alignment with the needle-receiving aperture therein and with the wire-threading aperture in said jaws, means for applying suction to the interior of said chamber at its upper end and in a direction and amount to supply a flow of air to a base in said chamber sufficient to lift and float the base pneumatically at the top of said chamber and off the floor defined by said jaws, means for lowering the needle through the said needle-receiving aperture and through the base in said chamber into registry with said wire-threading aperture during the application of the suction whereby the base is free to adjust slightly within the chamber to ensure entry of the needle therethrough, means for then lowering the chamber member, jaws and needle in unison to cause the lead-in wire to enter said needle by way of the said wire-receiving aperture, means for then causing the said jaws to open and uncover the bottom of said chamber member during continued movement of said chamber member to carry the base therein along the needle and the lead-in wire and onto the bulb in said holder, and means for terminating the suction when said chamber member has approached its lowered position.

3. A base-threading mechanism comprising a main slide, means mounting said slide for vertical reciprocation, a base-receiving chamber member carried by said slide, said chamber member being open at its bottom and including a roof having a needle-receiving aperture therein and sides adapted to enclose a base at least partially around its periphery, a pair of jaws pivotally mounted on said slide and arranged, when closed, to cover the bottom of said chamber and define a floor therefor, said jaws having their meeting faces shaped to define a funnel-shaped wire-threading aperture aligned with said needle-receiving aperture, a sub-slide mounted on said main slide for vertical reciprocation relative thereto, a hollow threading needle mounted for vertical reciprocation in said sub-slide above said chamber member and in alignment with the needle-threading aperture therein and with the wire-receiving aperture in said jaws, means for moving said

needle downward through the said needle-receiving aperture and through the base in said chamber into registry with the wire-receiving aperture in said jaws, and means to apply a differential air pressure within the interior of said chamber member in a direction and amount to supply a flow of air to a base in said chamber sufficient to lift and float the base pneumatically at the top of said chamber and off the floor defined by said jaws during movement of said needle downward through the chamber member.

4. A base-threading mechanism comprising a main slide, means mounting said slide for vertical reciprocation, a base-receiving chamber member carried by said slide, said chamber member being open at its bottom and including a roof having a needle-receiving aperture therein and sides adapted to enclose a base at least partially around its periphery, a pair of jaws pivotally mounted on said slide and arranged, when closed, to cover the bottom of said chamber and define a floor therefor, said jaws having their meeting faces shaped to define a funnel-shaped wire-threading aperture aligned with said needle-receiving aperture, a sub-slide mounted on said main slide for vertical reciprocation relative thereto, a hollow threading needle mounted for vertical reciprocation in said sub-slide above said chamber member and in alignment with the needle-threading aperture therein and with the wire-receiving aperture in said jaws, means for moving said needle downward through the said needle-receiving aperture and through the base in said chamber into registry with the wire-receiving aperture in said jaws, and means to apply a differential air pressure within the interior of said chamber member in a direction and amount to supply a flow of air to a base in said chamber sufficient to lift and float the base pneumatically at the top of said chamber and off the floor defined by said jaws during movement of said needle downward through the chamber member, the last-named means including suction means connected to passages in said chamber member opening into the upper end of said chamber at a location whereat the mouths of the openings are spaced from the base so as to be unobstructed by the base during its flotation at the top of the chamber.

5. A base-threading mechanism comprising a main slide, means mounting said slide for vertical reciprocation, a base-receiving chamber member carried by said slide, said chamber member being open at its bottom and including a roof having a needle-receiving aperture therein and sides adapted to enclose a base at least partially around its periphery, a pair of jaws pivotally mounted on said slide and arranged, when closed, to cover the bottom of said chamber and define a floor therefor, said jaws having their meeting faces shaped to define a funnel-shaped wire-threading aperture aligned with said needle-receiving aperture, a sub-slide mounted on said main slide for vertical reciprocation relative thereto, a hollow threading needle mounted for vertical reciprocation in said sub-slide above said chamber member and in alignment with the needle-threading aperture therein and with the wire-

receiving aperture in said jaws, means for moving said needle downward through the said needle-receiving aperture and through the base in said chamber into registry with the wire-receiving aperture in said jaws, and means to apply a differential air pressure within the interior of said chamber member in a direction and amount to supply a flow of air to a base in said chamber sufficient to lift and float the base pneumatically at the top of said chamber and off the floor defined by said jaws during movement of said needle downward through the chamber member, said last-named means including air pressure means connected by passages in said jaws opening upward toward the interior of the chamber member to direct air jets into the interior of a base therein.

15 6. A base-threading mechanism comprising a main slide, means mounting said slide for vertical reciprocation, a base-receiving chamber member carried by said slide, said chamber member being open at its bottom and including a roof having a needle-receiving aperture therein and sides adapted to enclose a base at least partially around its periphery, a pair of jaws pivotally mounted on said slide and arranged, when closed, to cover the bottom of said chamber and define a floor therefor, said jaws having their meeting faces shaped to define a funnel-shaped wire-threading aperture aligned with said needle-receiving aperture, a sub-slide mounted on said main slide for vertical reciprocation relative thereto, a hollow threading needle mounted for vertical reciprocation in said sub-slide above said chamber member and in alignment with the needle-threading aperture therein and with the wire-receiving aperture in said jaws, means for applying suction to the interior of said chamber member at the top thereof and in a direction and amount to create a flow of air to and around a base in said chamber sufficient to lift and float the base pneumatically at the top of the chamber and off the floor defined by said jaws, means for moving said main slide downward, means constraining said sub-slide to move downwardly with said main slide, means operable upon the initial downward movement of the main slide to effect downward movement of said needle relative to said sub-slide to carry it through the needle-receiving aperture in said chamber and through a base therein into registry with the wire-receiving aperture in said jaws during application of said suction, means for subsequently terminating downward movement of said sub-slide, and means connecting said jaws with said sub-slide and operable upon the termination of downward movement of said sub-slide to effect separation of said jaws upon continued downward movement of said main slide together with the chamber member therein, and means for terminating the suction when the chamber member has approached its lowered position.
